A. H. BEIRNES

OIL BURNER

Filed Oct. 16, 1926

Inv. by
A. H. Beirnes

Beirnes

UNITED STATES PATENT OFFICE.

ALFRED H. BEIRNES, OF WINNIPEG, MANITOBA, CANADA.

OIL BURNER.

Application filed October 16, 1926. Serial No. 142,021.

The invention relates to improvements in oil burners and an object of the invention is to provide an oil burner which can be used in all kinds of heaters such as furnaces, 5 stoves, hot water boilers and the like and which comprises comparatively few parts which can be readily constructed and installed and which when in operation effectively mixes fuel oil and air to produce an 10 intense flame of great volume.

A further object of the invention is to construct the burner so that the oil fed thereto can be initially quickly vaporized and subsequently mixed with air in a mixing chamber 15 provided to form an initial mixture and further to arrange the structure such that further air is mixed with the said mixture to form a final gas which is burnt.

A further object of the invention is to construct the burner so that the outlet for the 20 gas to the furnace fire pot can be regulated to best accommodate the burner to the particular draft of the furnace or the like in which it is installed.

25 A further object is to provide a burner having means for returning any overflow of oil to a suitable point of discharge and where it can be readily collected.

With the above more important objects in 30 view, the invention consists essentially in the arrangement and construction of parts hereinafter more particularly described, reference being had to the accompanying drawing, in which:—

35 Fig. 1 is a vertical sectional view through my device as it appears mounted on the furnace grate and within the fire pot.

Fig. 2 is a plan view of the bowl.

40 Fig. 3 is an enlarged detailed vertical sectional view through a portion of the upper end of the cone and the adjacent portion of the bowl.

Fig. 4 is a perspective view of a portion of the cross bar of the casing.

45 In the drawing like characters of reference indicate corresponding parts in the several figures.

As before intimated, this burner can be utilized in all types of heaters and I have herein shown it as mounted in the ordinary 50 type of household furnace which presents

the grate 1, fire pot 2 and ash pit 3, such parts being not herein detailed as their construction is well known to one familiar with the art.

On the grate 1 place an annular row of fire bricks 4 and the space between the bricks and the wall of the fire pot is filled in in any suitable manner to prevent the escape of air as by employing cement 5. The 55 bricks form a support for the casing 6 of my burner which is thus elevated above the grate. The casing has the lower part thereof cylindrical and the upper end thereof flared inwardly or coned as indicated at 6' 60 and both ends thereof are open.

A cross bar 7 passes centrally across the open top of the casing and has the sides thereof tapered so as to spread the upgoing flame emanating from the burner. The bar 70 7 is supplied centrally with a screw threaded opening 8 and into this I screw thread the upper end of the feed pipe 9 which extends centrally downwardly into the casing and has the lower end thereof screw threading 75 centrally into the top 10 of the inverted bowl 11. An elbow 12 is secured to the upper end of the pipe 9 and is connected to further pipes 13 which pass to the exterior of the furnace in any suitable manner such 80 as by passing down through the grate and out through the ash door of the ash box 3. Fuel oil is fed through the latter pipes to the interior of the bowl.

The top of the bowl is provided with an 85 upstanding marginal flange or rib 14 which forms a pan 15 for the reception of oil or other material which can be ignited for initially heating the burner parts. A number of radially disposed ribs 16 are integrally 90 cast on the top of the bowl and by prodding these with a poker or a similar tool, one can turn the bowl and so adjust its vertical position in relation to the in-flaring upper end of the casing, it being remembered that the 95 bowl is screw threaded onto the lower end of the pipe 9. A lock nut 17 is provided for locking the bowl in any adjusted position on the pipe. Centrally the under face of the bowl is provided with a frusto-conical 100 shaped boss or facial extension 18, the purpose of which will be later described.

On the grate of the furnace I mount a metallic cone 19 which has the lower end thereof provided with a circumscribing channel 20 and the upper end thereof terminating in a comparatively heavy head 21 provided with an upstanding annular flange 22 which forms an oil cup or pocket 23 at the upper end of the cone. The boss 18 hereinbefore mentioned is adapted to enter this cup 23 and with the parts positioned as shown in Figure 1. It will be observed that the fuel oil admitted through the pipe 9, is fed, directly into the cup and is retained in this cup in a comparatively narrow cavity appearing between comparatively thick walls. An overflow pipe 24 leads from the channel 20 to the exterior of the furnace.

The bowl has the wall thereof curved as shown in Figure 1 and it will be readily seen that when the bowl is adjusted up or down on the pipe 9, the vertical distance between the bowl and the in-flaring upper end of the casing will be diminished or increased, thus controlling the draft.

When the burner is to be placed in a furnace, the bowl is set in regard to the in-flaring upper end of the casing to best accommodate the draft conditions of such furnace and it is then locked in place by the nut. The cone is mounted on the grate so that it will then take a position in relation to the top of the bowl such as shown so that there will be a comparatively thin flow of oil in the pocket.

One starts the burner by putting oil, waste or other material which can be initially burnt into the pan 15. As such ignited material burns, it heats the adjoining portions of the burner and particularly the comparatively thick walls of the bowl top and the cone top. When these parts have become intensely hot, one permits oil fuel to pass through the pipes 13 and 9 into the cup and this oil fuel entering the cup will become immediately gasified and will pass out of the cup into the bowl, the interior of the bowl being at such time filled with air admitted through the grate.

The bowl in this way forms a mixing chamber for the gas and air and the mixture flows outwardly around the lower edge of the bowl and up into the annular passage 25 between the bowl and the casing and there mixes with further air passing up between the bowl and the casing. This final mixture is lit and burns with an intense annular flame which appears in the annular space 25 and appears also at the top of the casing. The heat developed by the burner after it has been going a short time, effectively gasifies the oil feeding into the cup from the feed pipe.

I wish here to point out that the lower end of the bowl is contracted and this causes a building up of pressure in the mixture

within the bowl so that it is forced out under pressure to flow around the bottom of the bowl and up into the passage 25.

What I claim as my invention is:—

1. The combination with a supporting grate, of a casing mounted on the grate and having the upper and lower ends thereof open and the upper end inwardly flaring, an inverted bowl suspended for vertical adjustment within the casing and underlying the inwardly flaring upper end of the casing, said bowl forming an internal mixing chamber and an exterior annular passage between the bowl and the casing, a cone shaped member mounted centrally on the grate and extending upwardly within the bowl and provided at the upper end with an oil receiving cup centrally underlying the closed upper end of the bowl and a feed pipe for fuel oil passing through the closed upper end of the bowl and delivering into the cup. 70 75 80

2. The combination with a supporting grate, of a casing mounted on the grate and having the upper and lower ends thereof open and the upper end inwardly flaring, an inverted bowl suspended for vertical adjustment within the casing and underlying the inwardly flaring upper end of the casing, said bowl forming an internal mixing chamber and an exterior annular passage between the bowl and the casing, a cone shaped member mounted centrally on the grate and extending upwardly within the bowl and provided at the upper end with an oil receiving cup centrally underlying the closed upper end of the bowl, a feed pipe for fuel oil passing through the closed upper end of the bowl and delivering into the cup, a channel located on the base of the cone and a drip pipe leading from the channel. 90 95 100

3. The combination with a supporting grate, of a casing mounted on the grate and having the upper and lower ends thereof open and the upper end of the casing inwardly flared and provided with a centrally located cross bar, a vertically disposed oil feed pipe carried centrally by the cross bar and entering the casing, an inverted bowl mounted on the lower end of the pipe and underlying the flaring end of the casing and providing an interior mixing chamber within the bowl and an exterior annular passage between the bowl and the casing, a cone mounted centrally on the grate and extending upwardly within the bowl and provided at the upper end with a cup centrally underlying the closed end of the bowl and adapted to receive oil from the feed pipe and at the lower end with a circumscribing drip channel and a drip pipe leading from the channel. 110 115 120 125

4. The combination with a supporting grate, of a casing carried by the grate and having the upper and lower ends thereof open and the upper end inwardly flared, a 130

suitably supported oil feed pipe extending downwardly within the casing, an inverted bowl adjustably mounted on the lower end of the feed pipe and contained within the casing and providing within the bowl a mixing chamber and between the bowl and the casing, an annular passage, said bowl underlying the flaring upper end of the casing and having the closed end thereof presenting an oil pan and provided with an inwardly extending boss on the inner side

surrounding the oil pipe, a cone mounted centrally on the grate and extending upwardly within the bowl, said cone being provided at the lower end with an oil receiving channel and at the upper end with an oil receiving cup receiving the boss aforesaid and a drip pipe leading from the channel.

Signed at Winnipeg, this 1st day of October, 1926.

ALFRED H. BEIRNES.
